INVENTOR

VERA OCKFEN

BY

Richard J. Cook

ATTORNEY

UNITED STATES PATENT OFFICE.

VERA OCKFEN, OF SPANAWAY, WASHINGTON.

CROCHET HOLDER.

Application filed September 11, 1923. Serial No. 662,059.

To all whom it may concern:

Be it known that I, VERA OCKFEN, a citizen of the United States, and a resident of Spanaway, Pierce County, Washington, have 5 invented certain new and useful Improvements in Crochet Holders, of which the following is a specification.

This invention relates to boxes for holding thread, crochet cotton, yarn, and the like, and has for its principal object to provide a box of that character embodying bearing sockets in its opposite side walls wherein the ends of a spool mounting shaft may be removably and revolubly held so 10 that the thread, or yarn, can be unwound from a spool and drawn outwardly through a hole in the box cover.

Other objects reside in the novel features of construction for holding the spool mounting shaft and whereby a spool may be properly held thereon.

In accomplishing these and other objects of the invention, I have provided the improved details of construction, the preferred forms of which are illustrated in the accompanying drawings, wherein—

Figure 1 is a perspective view of a thread holder embodying the present invention.

Figure 2 is a central, vertical section of 30 the same.

Figure 3 is a horizontal section through the holder.

Referring more in detail to the drawings—

1 designates what may be a cylindrical, 35 metal box with a closed bottom wall 2 and a removable cover 3 fitted over its upper end; the cover being provided centrally with an opening 4 through which thread, or yarn may be withdrawn from the box.

40 Formed vertically in opposite side walls of the box are outwardly pressed grooves 6 and 7 that extend from the upper edge of the box to points about half way of its height, and at their lower ends they lead 45 into sockets 8—9 within which the opposite end points 11—12 of a spool mounting shaft 13 are revolubly and removably held.

Fitted onto the shaft 13 is a conically tapered, flexible sleeve 14 over which a spool 15 on which thread or yarn 16 is wound, is removably mounted. From the spool the strand 17 of thread or yarn is extended through the opening 4 in the cover, and as it is drawn out, the spool will revolve to permit unwinding.

55 When the thread or yarn is exhausted, the cover 3 can be removed from the box, the shaft 13 unseated and removed, the old spool slipped from the shaft 13, a new one put in its place and the shaft returned to 60 the box.

Such a device can be made in desirable sizes, and thread or yarn therein will be kept free from dirt or from being otherwise soiled.

65 Having thus described my invention, what I claim as new therein and desire to secure by Letters-Patent, is:

1. A device of the class described, comprising a container fitted with a removable 70 cover having a perforation therein, channels leading downwardly from the upper edges at opposite sides of the container and terminating in sockets at their lower ends, and a spool mounting shaft with tapered ends 75 revolubly fitted in said sockets and adapted to be removed from the container through said channels.

2. A device of the class described comprising a container fitted with a removable 80 cover having a central perforation, channels leading downwardly from the upper edge at opposite sides of the container and terminating in sockets at their lower ends, a shaft having its opposite ends revolubly 85 and removably held in said sockets and adapted to be fitted from the container through said channels and a conically tapered, flexible spool mounting sleeve on said shaft.

86 Signed at Takoma, Pierce County, Washington, this 11th day of July, 1923.

Mrs. VERA OCKFEN.
